TAMPON APPLICATOR ASSEMBLY CONDITIONING METHOD AND APPARATUS

John M. Graef and Kenneth J. Harwood, Neenah, and Reinhardt N. Sabee, Appleton, Wis., assignors to International Cellucotton Products Company, Chicago, Ill., a corporation of Delaware

Application May 13, 1949, Serial No. 93,044

12 Claims. (Cl. 19—144.5)

1

This invention relates to a method and apparatus for softening an end portion of a catamenial tampon which projects from an end of a tampon applicator structure, and to a method and apparatus for accurately positioning the tampon in the applicator, positioning the components of the applicator in proper relation to each other, and releasably locking the applicator parts in their properly assembled relationship.

The tampons which are treated by the method and apparatus of this application comprise a more or less cylindrical, elongated plug of absorbent material, and the applicator structure comprises a pair of paper tubes, one of which is telescoped into the other and is adapted to be pushed forward therein for ejecting the tampon which is seated in a portion of said other tube.

It is desirable that an end portion of the tampon project slightly from the front end of the applicator structure and that such projecting portion be spread or mushroomed so as to overlie the end of the applicator tube. In certain manufacturing procedures, the tampons are made of substantially cylindrical form so that they lack a headed end which can overlie the applicator end and, in other procedures of tampon manufacture, tampons are initially formed with end heads but by the time the tampons are assembled with the applicator tube they may not always maintain sufficient spread to satisfactorily overlie the applicator tube end.

One of the important objects of the present invention is to provide a method and apparatus for effecting softening and spreading of an end portion of a tampon which projects from an applicator tube so that in the finished product a soft, down-like end will project from the applicator tube end to adequately cover such end.

Another important object of the invention is to provide means for automatically adjusting the position of the telescopically fitting tube elements relative to each other and the position of the tampon in one of said tube elements so as to provide the desired amount of tampon projection from the applicator tube.

Still another important object of the invention is to provide a method and apparatus for forming a releasable lock in the applicator structure to retain the applicator tubes in their properly adjusted relationship to each other.

Other objects of the invention are to provide a method and apparatus of the character indicated, which will speedily and effectively perform its indicated operations; to provide such mechanism which will operate automatically without the at-

2

tention of an operator, and other objects and advantages of the invention will be understood by reference to the following specification and accompanying drawings (8 sheets) in which there is illustrated a selected embodiment of apparatus for carrying out the method and performing the said operations on a tampon and tampon applicator structure.

In the drawings,

Fig. 1 is a plan;

Fig. 2 is an end elevation of the lower end of the structure as viewed in Fig. 1;

Fig. 3 is a side elevation of the left-hand side of Figs. 1 and 2;

Fig. 4 is an end elevation of the upper end of the mechanism as viewed in Fig. 1 and the left-hand side of Fig. 3;

Fig. 5 is a section on a plane approximately represented by the line 5—5 on Figs. 1 and 3;

Fig. 6 is a section on a plane approximately represented by the line 6—6 on Figs. 1, 2, 4 and 7;

Fig. 7 is a plan section on the plane approximately represented by the line 7—7 of Fig. 6;

Fig. 8 is a vertical section on the plane represented approximately by the line 8—8 on Figs. 1 and 2;

Fig. 9 is a section on the line 9—9 of Fig. 7 but on an enlarged scale;

Fig. 10 is an end elevation of an element appearing in section in Fig. 9, and

Fig. 11 is a perspective illustration of a tampon and applicator structure as it appears after it has been conditioned by the apparatus herein shown.

The tampon and applicator structure shown in Fig. 11 comprises a generally cylindrical, elongated tampon body 1 which is seated in a tubular applicator member 2 which is usually made of paper. A front end portion 3 of the tampon 1 projects from the front end of the applicator tube 2 and is slightly enlarged so as to extend sideways over the end of the applicator tube 2. An ejector tube 4 has an end portion telescoped into the rear end portion of the applicator tube 2, the

front or inner end of the ejector tube being seated against the rear end of the tampon as indicated. The tampon is provided with a withdrawal cord 1a which may be in the form of an extension of a jacket or wrapper enclosing the

tampon, as herein shown, or in the form of separate string or cord tied or otherwise attached to the tampon body.

The tube 4 is a fairly free but frictionally sliding fit in the tube 2. In order to insure retention of the tube 4 in the tube 2, a lock is provided

as indicated at 5, this lock consisting of a pair of triangular ears simultaneously punched into the tubes as shown in somewhat greater detail in Fig. 8.

The specific details of the structure of the tampon and the applicator tubes are not important in connection with the present invention and the foregoing described general arrangement typifies the general class of tampons and applicator structures which are conditioned by the method and apparatus about to be described. Such tampon and applicator structures are delivered to the apparatus in assembled relation generally closely approximating the final assembled relation as represented in Fig. 11, but not necessarily in the exact relation desired and lacking the locking feature indicated at 5.

The apparatus about to be described adjusts the tampon inwardly or outwardly of the tube 2 as may be required to obtain the desired relationship, and it also adjusts the ejector tube 4 relative to the outer tube 2, forms the lock 5 and effects softening and spreading of the projecting end portion 3 of the tampon.

The tampon carrying applicator structure are delivered in their initially but possibly inaccurately assembled relationship through a delivery chute 6 (Figs. 2 and 5) which is arranged to cause the tubes to roll by gravity in side by side relationship to the receiving point of the apparatus.

By reference to Figs. 1, 5 and 6, it will be seen that the articles to be conditioned are deposited by gravity on arcuate end portions 7 of a pair of strap-like table members 8 and 9 which are suitably supported at their ends by attachment to cross members 10, 10 of a frame structure. The cross members 10 are supported by upstanding side frame members 11, 12 and 13 which extend upwardly from suitable base members 14, 14.

The articles to be conditioned are propelled over the lengths of the table straps 8 and 9 by a conveyor structure, which comprises a pair of conveyor chains 15 and 16 (see Figs. 5 and 6) which are supported by pairs of sprockets mounted on shafts 17 and 18 which are suitably journaled in the side frames 12 and 13. The conveyor chains 15 and 16 are interconnected by a plurality of cross bars 19 at regularly spaced intervals and these cross bars are each provided with means for engaging and propelling the articles over the table straps 8 and 9. In this instance, the cross bars 19 are each provided with three pins 20 which are operative to engage and propel the articles as aforesaid. The outermost pins 20 are disposed so as to travel along a path adjacent the outer side edges of the table straps 8 and 9 and the intermediate pin 20 travels along a path between the adjacent edges of the said table straps. As indicated, the pins 20 are rigid with the respective cross bars 19 and each cross bar is secured to a link of each chain 15 and 16 so that the chains and their article-propelling pins may flex around the sprockets as shown in Fig. 5.

The conveyors are driven step by step through the agency of a Geneva movement which is associated with one end of the shaft 17 which is projected through the side frame member 13 (see Figs. 2 and 8).

The Geneva drive movement comprises a radially slotted driven member 21 and the usual holding disc 22, these members being integrally united through a hub 23. The driven member 21

is rotatably mounted on the hub 24 of a flange or disc 25 which is fixedly secured to the conveyor drive shaft 17 by suitable means such as a set screw 26.

The driven member 21 is adjustably secured to the flange or disc 25 through the agency of a series of bolts 27 (Fig. 2) which are carried by the slotted disc 21 and extend through suitably arched slots, such as the slot 28 (Fig. 2) which permits a desirable amount of relative rotary adjustment between the driven member 21 and the mounting member 25. The driven member 21 is actuated by the usual crank pin or driver 29 carried by a shaft 30 which is rotatably journaled in the side frames 11, 12 and 13. Said shaft 30 also carries the usual element 31 for cooperating with the locking disc 22 to hold the driven shaft 17 against rotation during the rest periods of the driven structure.

The driving element 29 of the Geneva motion is continuously driven by means of a gear 32 (Fig. 4) which meshes with another gear 35 that is secured to a shaft 36 which is journaled in the side frame members 11 and 12 (see Fig. 6). The shaft 36 also carries a worm wheel gear 37 which meshes with a worm gear 38 on a longitudinal shaft 39 (see Figs. 1 and 4) which shaft is suitably journaled in brackets 40 and 41 which are secured to and extend laterally from the side frame member 11. The shaft 39 is extended beyond the supporting bracket 41 and is provided with a gear 42 and this gear 42 meshes with a driving pinion 43 on another shaft 44 which is also journaled in the said brackets 40 and 41. The shaft 44 is driven by being connected to a suitable source of power, a drive being shown in this instance as comprising a driving pulley 45 and a belt 46. It will be seen that through the described gear connections, the driving shaft 30 of the Geneva motion is continuously rotated and that through the Geneva motion the conveyor structure will be advanced step by step.

By reference to Fig. 5, it will be seen that the pins 20 of the conveyor structure will be operative to pick up the lowermost article in the delivery chute 6 so as to withdraw the article from the chute and to advance it step by step over the surfaces of the table straps 8 and 9. The table strap 9 has two surface portions 9a and 9b at different levels separated by a vertical shoulder 9c (see Figs. 6 and 7). The surface portion 9a is in the same plane as the top surface of the table member 8 and cooperates therewith to support the outer tube portions 2 of the article being conditioned. The depth of the shoulder 9c is approximately the same as the thickness of the paper material of which the tubes 2 are formed so that the relatively elevated surface portion 9b of the table member 9 will support the ejector tubes 4 of the article. The shoulder 9c is formed with a receiving portion 9d (Fig. 7) which is outwardly offset relative to the remainder of said shoulder, said receiving portion 9d being connected to the main portion of the shoulder by an angularly disposed portion 9e.

This angularly disposed portion 9e of the shoulder constitutes a cam which engages the adjacent ends of the successive tubes 2 to cam the same forwardly into a predetermined desired relationship to the adjacent face of a side wall member 47 which extends upwardly from the frame member 12. A similar side wall member 48 extends upwardly from the frame member 13 and operates with the member 47 to provide side

guides which define a path of travel for the articles. These side guides 47 and 48 are preferably made of material having very smooth faces so as to avoid friction and abrasive action on the ends of the article. Strips of synthetic glass-like material (such as Lucite) are very satisfactory for the purpose of these side guides although other materials may be employed.

As shown in Fig. 7, the cam portion 9e of the shoulder 9c acts to move the tampon structure toward the side plate 47. This serves to bring the tampon structure into operating position within relatively narrow confines while permitting the tampon to be delivered by the chute 6 within relatively wider limits.

In the first operating station indicated at A in Fig. 7, the inner tube element 4 may be pressed into the outer tube 2 to preliminarily adjust the tube 4 relative to the tube 2. In some instances, the tube 4 may not actually be moved relative to the tube 2, i. e. where the position of the tube 4 in the tube 2 is initially satisfactory or when the tube 4 is initially too far into the tube 2. The tube adjusting means in this station A comprises a plunger 49 which is mounted for horizontal reciprocation through a sufficiently long path of travel to insure that the tube 4 will be inserted into the tube 2 at least the required distance. Engagement of the end or head portion 3 of the tampon with the side guide 47 and seating of the end of the tube 2 against said portion of the tampon serves to prevent endwise movement of the tube 2 under endwise directed forces transmitted thereto by the ejector tube 4 when the latter is adjusted inwardly by the action of the plunger 49. This plunger 49 serves also to move the entire tampon and applicator assembly toward the side guide 47 in the event that the shoulder 9c has failed to do so. Such endwise movement of the entire assembly will occur when possible, because of the low friction between the tampon applicator structure and the table elements 8 and 9 and certain overlying hold-down members which will hereafter be explained, as compared with a higher degree of friction between the interengaging surfaces of the telescoped tubes.

The plunger 49 is carried by a cross head 50 which is secured to a pair of cross rods 51 and 52 which are slidably mounted in the side frames 12 and 13. Outwardly of the side frame 12, the slide rods 51 and 52 are rigidly interconnected by a cross head 53 (see also Figs. 4 and 6). The cross head 53 is provided with a laterally extending lug 54 which carries a depending roller 55 and this roller rides in a cam groove or track 56 in a cam wheel 57 which is secured to the shaft 36. The shaft 36 is continuously driven as already explained, and it will be seen that the cam member 57 will act through the roller 55 to reciprocate the slide rods 51 and 52 with a regular uniform, in and out motion which is determined by the formation of the cam track 56. The speed of the rotation of the shaft 36 and cam 57 and the shape of the cam track 56 are such that the slide rods 51 and 52 are given one complete reciprocation (back and forth) for each step of movement of the conveyor structure. Hence, each tampon structure which reaches the position A (Fig. 7) will be subjected to the action of the plunger 49.

In the next station B, a plunger 58 acts against the adjacent end portion 3 of the tampon to push the tampon inwardly of the holder tube 2, the tube being held against endwise movement under the force of the plunger 58 by engagement with

the shoulder 9c. The plunger 58 is of relatively small diameter as compared with the diameter of the tampon and it acts against substantially a central portion of the tampon so that the tampon may readily be compressed and inserted into the tube 2 in the event that it is delivered to the station B in a condition of excess projection from the tube.

The plunger 58 is slidably mounted in the cross head 53 and is provided at its outer end with collar 59 having an endwise extending ear 60. This ear 60 is pivoted to one end of a rock lever 61 which has its other end pivoted to one end of a link 62 which is pivotally anchored as indicated at 63, to the lug 54. The rock lever 61 is pivoted as indicated at 64, intermediate its ends for rocking movement. The pivot mounting 64 for the rock lever may consist of a pin extending transversely through the lever 61 and a bracket projecting from the side frame 11 and provided with slotted arms as indicated, for receiving the ends of the pin. From an inspection of Fig. 6, it will be seen that when the slide rods 51 and 52 and the cross head 53 are moved to the left, the rock lever 61 will be rocked so as to thrust the plunger 58 inwardly so as to press the tampon into the tube 2 and that when the slide rods 51 are moved to the right, the plunger pin 58 will be retracted or withdrawn.

When the tampon structure is delivered into the position C, it is then located between a plunger 65 carried by the reciprocating head 50 and a plunger pin 66 carried by the other reciprocating cross head 53. In the position C, the side guide 47 is provided with a recess 67 having a funnel-like entrance portion 68 and a stop shoulder 69 which is adapted to be engaged by the adjacent end of the tampon tube 2. Movement of the plunger 65 toward the side guide 47 serves to press the tampon structure into the recess 67, the funnel portion 68 serving to more or less compress and thereby perfect the shape of the projecting end portion of the tampon, the shoulder 69 serving to limit movement of the tube 2 while the end of the tampon is permitted to abut the bottom of the recess 67. This constitutes also a step in which the extent of projection of the tampon end portion 3 from the tube 2 is subjected to adjustment. Inasmuch as the plunger 65 acts through the ejector tube 4, it will be seen that the tube 4 will normally be urged into the tube 2 until the front end of the tube 4 seats against the adjacent end of the tampon body as shown.

Upon return movement of the plunger 65, the oppositely disposed plunger 66 will eject the tampon end portion from the recess 67 so as to free the tampon structure for continuation of its lateral movement between the side guides 47 and 48.

During the operations of the plungers 49, 58, 65 and 66, and during other operations which will presently be explained, the tampon structures are held down against the supporting straps 8 and 9 by means of overlying straps or bars 70 and 71. These members 70 and 71 are supported by the side frames 12 and 13 by suitable supporting brackets 72 and 73 as will be understood by reference to Figs. 1, 3 and 5. These hold-down members 70 and 71 may also advantageously be formed of smooth surfaced, transparent material such as glass or, preferably, transparent synthetic material (such as Lucite). The hold-down member 71 is arranged to have its inner edge in vertical alignment with the shoulder 9c so as to cooperate

with the latter, as best shown in Fig. 8, for positioning the applicator tube 2.

The plungers which reciprocate through suitable openings in the side members 47 and 48 do not necessarily bear on the walls formed by the openings through which said plungers reciprocate. They are preferably a free sliding fit in said openings.

The plungers 49, 58 and 65 and the shoulders 5c and 69 function as explained, to adjust the elements of the tampon and applicator structure inwardly and outwardly relative to each other to insure their positioning in the desired relationship.

After the station C there are two idle stations and then a station D in which the projecting end portion 3 of the tampon is subjected to a fluffing operation which softens said end portion. This softening is effected by means of a pricking or chopping device which is simultaneously rotated and reciprocated. Said device comprises a more or less cylindrical head 74 (Figs. 1 and 9) which is rotatably mounted on a shaft 75 which projects from a carrier 76. The cylindrical head 74 is rotated on the shaft 75 by means of a belt 77 which extends around said head 74 and around a pulley 78 which is mounted on a shaft 79. The shaft 79 is journaled in suitable bearing brackets 80 which are mounted on the side frames 11 and 12.

The shaft 79 is driven at fairly high speed from the continuously driven shaft 39 through the agency of a driving belt 81 and pulleys 82 and 83 on the shafts 39 and 79 respectively (Fig. 4).

The cylindrical head 74 is provided with a series of sharp pins or teeth 84 projecting endwise therefrom, said teeth being adapted to be driven into the tampon end portion 3 to thereby separate the fibers so as to effect the desired softening and fluffing. Such softening is especially desired around the outer edges of the tampon end portion and for that reason the teeth 84 are formed in an annular arrangement which results from counter-boring of the head as best shown in Figs. 9 and 10. Also, as shown in those figures, the counter-bore 85 is eccentrically rated to the axis of the head 74 so that the teeth at one side are slightly wider than at the other. Inasmuch as the softening member 74 is rotated, it will be apparent that this widening of some of the teeth will result in a more or less gradual change in the softness of the tampon end portion from the center of the tampon end towards its outer edges.

The softening head 74 is supported for reciprocation by the carrier 76, the latter being pivoted on the upper ends of a pair of parallel links 86 and 87 (Fig. 3), the lower ends of which are pivoted on a bracket 88 which is secured to the frame structure. The parallel links 86 and 87 are relatively offset laterally as will be understood by reference to Fig. 4, the upper end of the link 86 having an offset portion connected to the carrier 76 in alignment with the upper end portion of the link 87. For reciprocating the carrier 76, there is provided a rock lever 88 which has its upper end pivoted as indicated at 90, to the carrier 76 and its lower end pivoted as indicated at 90, to a link or connecting rod 91 which has its other end connected to a crank pin 92. The crank pin 92 is carried by a disc 93 secured to an end of the constantly driven shaft 44 (see Figs. 1 and 4).

The rock lever 88 has a floating intermediate

5 pivot 94 carried by a short link 95 which has its other end anchored as shown at 96, on another link 97. The link 97 is adjustably supported at its lower end on a pin, as indicated at 98, in a lug or boss projecting from the side frame 11, means such as a set screw being provided to lock the link 97 in selected position of adjustment on said pin 98. This floating pivot arrangement for the rock arm 88 avoids the need for any loose connection between the reciprocating parts which would be somewhat objectionable in a structure of this type when operated at high speeds as designs for the purposes of this mechanism.

10 The softening head 74 is constantly rotated and 15 constantly reciprocated so that during the progress of a tampon structure from station C to the softening station D and in its subsequent progress from said station D substantially the entire face of the tampon end will be subjected to the action 20 of the softening head. By its in and out chopping or pricking action, the fibers of the tampon material will be more or less separated from each other and the end portion of the tampon will be spread outwardly or mushroomed so as to produce 25 an end portion which is soft as compared with the main body of the tampon. Also because of the widening of some of the teeth, the softness will be somewhat amplified towards the periphery of the tampon end and gradually less towards the 30 center thereof. It will, of course, be understood that the peripheral portion of the tampon end 3 is mainly acted upon by the softener 74 during the rest period of the tampon unit in station D. However, as already indicated, owing to the movement of the tampon unit into and out of the station 35 D, substantially the entire area of the tampon will be acted upon.

40 During the operation of the softening head 74, the tampon is held against endwise displacement by its seating on the inner end of the tube 4 and by engagement of the tube 4 at its outer end with a shoulder portion or raised seat 99 formed on the side member 48.

45 From the station D, the article is propelled to a station E. In that station the lock 5 is formed. Preliminary to punching of the lock 5, a presser 100 (Figs. 1, 3 and 7) is moved inwardly into engagement with the now softened head 3 of the tampon. This presser 100 does not exert compacting force on the tampon head but flattens or smooths its end and at the same time presses the applicator member 2 endwise until its opposite end seats against the shoulder 9c as shown in Fig. 7. This serves to accurately position the 50 tampon applicator structure for the purpose of the mechanism which forms the lock 5.

55 The presser head 100 is carried by a shaft 101 which is slidably mounted in suitable bearing brackets carried by the side frames 11 and 12. 60 The shaft 101 has a squared portion 102 intermediate its ends which is connected by a pivot pin 103 to one end of a rock lever 104 which is pivoted intermediate its ends as indicated at 105, on a bracket 106 which is supported by the previously 65 mentioned bracket 80. The other end of the rock lever 105 is pivoted as shown at 107, to a link 108 which is pivoted to a portion of the reciprocating bracket 53. Incident to reciprocation of the bracket 53 the rock lever 105 will be rocked about its pivot 105 and the presser head 100 will be reciprocated toward and from the tampon to effect the above-mentioned operations.

70 The lock 5 is produced by means of a punch 109 of substantially triangular form with a sharpened 75 bevel end 110 which is operative to cut and press

inwardly triangular ears, as indicated in Figs. 7 and 11. These ears are cut out of both the outer and inner tubes 2 and 4, one over the other, since in the zone of operation of said punch, a portion of the tube 4 is located within the tube 2. The triangular ears punched inwardly by the punch are offset inwardly to such an extent that the ear formed from the outer tube 2 projects through the hole left in the inner tube portion by the ear pressed therefrom; hence, the inner tube will be locked against rearward displacement from the outer tube. Nevertheless, because the ears are readily returnable to their normal positions in the tubes, they do not offer significant resistance to forward movement of the inner tubes 4 into the outer tubes to eject the tampons.

The punch 109 is suitably secured in the free end of an arm 111 of a bell crank which is pivotally mounted for rocking movement, as indicated at 112 in a bracket 113. The bracket 113 is mounted on the side frame 13 through the agency of another bracket 114 which is of more or less angle form in cross section and elongated to extend over most of the length of the side frame 13. This bracket 114 is provided with a pair of upwardly extending arms 115 which pivotally support between them a fluid pressure cylinder 116. The cylinder 116 contains a piston 117 and a piston rod 118 which are slidably axially of the cylinder, the outer end of the piston rod 118 being connected as indicated at 119 to the free end of the other arm 120 of the last-mentioned bell crank.

Fluid pressure admitted through the inlet pipe 121 of the cylinder 116 serves to urge the piston outwardly, thereby to rock the bell crank and press the punch 109 into the applicator structure thereunder in station E of the apparatus. A coil spring 122 disposed in the cylinder between the piston 117 and the outer end of the cylinder serves to retract the piston and the punch when the fluid pressure in the cylinder is relieved.

Fluid pressure to the cylinder 116 is controlled by a valve 123 (Fig. 2) which is fixedly mounted on a bracket 124 which is attached to the frame members 11 and 12 (see also Fig. 1). The valve 123 is in the form of a cylinder having a piston 125 movable therein from a position in which it establishes communication between ports to which pipes 126 and 127 are connected, or between ports to which the pipes 126 and 128 are connected. The pipe 128 represents the inlet pipe which communicates with a source of fluid pressure and the pipe 127 is an outlet or return pipe through which pressure fluid is relieved from the cylinder 116. When the piston 125 is in the position illustrated in dotted lines in Fig. 2, the pipes 126 and 127 are in communication, thereby relieving pressure from the cylinder 116. When the piston 125 is moved to the left, the port to the relief pipe 127 is closed and connection is made between the pressure supply pipe 128 and the pipe 126 to deliver fluid under pressure to said cylinder 116 to thereby rock the punch in lock forming direction.

The valve piston 125 has a piston rod 129 which extends from the valve cylinder and is provided at its free end with a roller 130 which is normally held in engagement with the roller 131 that is mounted on an arm 132 pivoted at its lower end in a suitable bracket provided for that purpose. The roller 131 rides against a peripheral cam formation 133 on one end of the cam disc 57 (see Fig. 1). Rocking movement imparted to the roller 131 by the cam 133 is transmitted to

the valve piston or core 125 to adjust the fluid pressure connections as required for the properly timed operation of the punch. A spring 134 in the valve cylinder 125 serves to normally bias the valve piston in a direction to maintain the roller 130 in engagement with the roll 131 and the latter in engagement with the cam 133.

From the station E, the processed tampon and applicator are discharged to a suitable receptacle or conveyor by which the tampon structure is removed and carried to stations for wrapping or other treatment as may be desired.

The described structure operates continuously and automatically without attention from an operator or, at least, with a minimum of watching, and its various operating parts are of simple and durable construction. Hence, the mechanism is operative continuously without lost time because of breakdowns or failures. Nevertheless, the mechanism performs relatively delicate operations on materials which are readily subject to damage if improperly handled.

Various changes in the described structure may be made without departing from the principles of the described apparatus and its method of operation.

We claim:

1. The method of conditioning a tampon structure which embodies a tampon partially telescoped into one end portion of an applicator tube and an ejector tube which is partially telescoped into the other end portion of the applicator tube, comprising the steps of propelling a tampon and applicator structure as aforesaid, laterally, step by step, in one position of rest of the structure applying pressure to the exposed end of the tampon while holding the applicator tube against endwise movement in the direction in which said pressure is applied to the tampon, and in a succeeding position of rest applying pressure to the exposed end of the ejector tube to urge the ejector tube to move inwardly of said applicator tube and the other end of said ejector tube into engagement with the tampon portion within the applicator tube while also holding said applicator tube against endwise movement in the direction in which said last mentioned pressure is applied.

2. The method of conditioning a tampon structure which embodies a tampon partially telescoped into one end portion of an applicator tube and an ejector tube which is partially telescoped into the other end portion of the applicator tube, comprising the steps of propelling a tampon and applicator structure as aforesaid, laterally, step by step, in one position of rest of the structure applying pressure to the exposed end of the tampon while holding the applicator tube against endwise movement in the direction in which said pressure is applied to the tampon, and in a succeeding position of rest applying pressure to the exposed end of the ejector tube to urge the ejector tube to move inwardly of said applicator tube and the other end of said ejector tube into engagement with the tampon portion within the applicator tube while also holding said applicator tube against endwise movement in the direction in which said last mentioned pressure is applied, and then, in another position of rest of the tampon structure, working the exposed end portion of the tampon to soften the same.

3. The method of conditioning a tampon structure which embodies a tampon partially telescoped into one end portion of an applicator tube and an ejector tube which is partially tele-

scoped into the other end portion of the applicator tube, comprising the steps of propelling a tampon and applicator structure as aforesaid, laterally, step by step, and, in positions of rest of said structure, applying pressure to the exposed end of the tampon while holding the applicator tube against endwise movement in the direction in which said pressure is applied to the tampon, applying pressure to the exposed end of the ejector tube to urge the ejector tube to move inwardly of said applicator tube and the other end of said ejector tube into engagement with the tampon portion within the applicator tube while also holding said applicator tube against endwise movement in the direction in which said last mentioned pressure is applied, working the exposed end portion of the tampon to soften the same, and punching registering locking tongues from the outer and inner tubes inwardly thereinto to resist separation of the inner tube from the outer tube.

4. In apparatus for conditioning an article embodying a tampon seated in an end portion of an applicator tube and projecting from an end thereof, and an ejector tube telescoped into the other end portion of said applicator tube and projecting therefrom, said apparatus comprising mechanism for effecting movement of such an article along a predetermined path of travel, means operative at one end of the article to press said tampon into said applicator tube, means operative at the other end of said article to press said ejector into said applicator tube, and means for punching registering ears inwardly of said applicator and ejector elements to provide a lock for resisting withdrawal of the ejector from said applicator, all of said means being operative on said article while in said path of travel.

5. In apparatus for conditioning an article embodying a tampon seated in an end portion of an applicator tube and projecting from an end thereof, and an ejector tube telescoped into the other end portion of said applicator tube and projecting therefrom, said apparatus comprising mechanism for effecting movement of such an article along a predetermined path of travel, means operative at one end of the article to press said tampon into said applicator tube, means operative at the other end of said article to press said ejector into said applicator tube, and means acting on the projecting end portion of the tampon to soften and spread the same into overlying relation to the adjacent end of the applicator tube, all of said means being operative on said article while in said path of travel.

6. In apparatus for conditioning an article embodying a tampon seated in an end portion of an applicator tube and projecting from an end thereof, and an ejector tube telescoped into the other end portion of said applicator tube and projecting therefrom, said apparatus comprising mechanism for effecting movement of such an article along a predetermined path of travel, means operative at one end of the article to press said tampon into said applicator tube, means operative at the other end of said article to press said ejector into said applicator tube, means acting on the projecting end portion of the tampon to soften and spread the same into overlying relation to the adjacent end of the applicator tube, means for pressing said softened tampon end and operative to effect predetermined, longitudinal positioning of said article, and means operative on said article when so positioned for punching registering ear portions from the applicator and

ejector tubes to form a lock therefor substantially as described, all of said means being operative on said article while in said path of travel.

7. In apparatus for conditioning an article embodying a tampon seated in an end portion of an applicator tube and projecting from an end thereof, and an ejector tube telescoped into the other end portion of said applicator tube and projecting therefrom, said apparatus comprising means for propelling said article transversely of its length, step by step, guide members spaced from each other and extending in the direction of travel of said article for maintaining said articles within a predetermined path of travel, one of said guide members being provided with a shoulder which extends in the direction of travel of said articles and which engages the ejector receiving end of said applicator tube for positioning said applicator tube, said shoulder having an offset end portion at the receiving end of the member and an angularly extending intermediate portion joining said offset end portion to said tube positioning shoulder, said angularly extending shoulder portion constituting a cam which is operative to move said applicator tubes endwise to align the ends of said tubes with said positioning shoulder as an incident to the travel of the tubes effected by said propelling means.

8. In apparatus for conditioning an article embodying a tampon seated in an end portion of an applicator tube and projecting from an end thereof, and an ejector tube telescoped into the other end portion of said applicator tube and projecting therefrom, said apparatus comprising means for propelling said article laterally, step by step, guide members spaced from each other to receive between them the transverse thickness of said articles, one of said guides being provided with a shoulder extending in the direction of travel of said articles and adapted to be engaged by the ejector receiving end of said applicator tube for positioning said applicator tube, reciprocating means operative in one position of rest of the article to engage the outer end of the ejector member to effect lengthwise movement of the article for positioning said applicator to permit engagement of said applicator end with said positioning shoulder, means operative in another position of rest of said article to engage the projecting tampon end portion so as to press the tampon inwardly of the applicator and the applicator against said position shoulder.

9. In apparatus for conditioning an article embodying a tampon seated in an end portion of an applicator tube and projecting from an end thereof, and an ejector tube telescoped into the other end portion of said applicator tube and projecting therefrom, said apparatus comprising means for propelling said article laterally, step by step, guide members spaced from each other to receive between them the transverse thickness of said articles, one of said guides being provided with a shoulder extending in the direction of travel of said articles and adapted to be engaged by the ejector receiving end of said applicator tube for positioning said applicator tube, reciprocating means operative in one position of rest of the article to engage the outer end of the ejector tube to effect lengthwise movement of the article for positioning said applicator tube to permit engagement of said ejector receiving end of said applicator tube with said positioning shoulder, means operative in another position of rest of said article to engage the projecting tampon end portion so as to

to press the tampon inwardly of the applicator tube and the applicator tube against said positioning shoulder, means operable in another position of the applicator tube to engage the free end of said ejector tube to effect endwise movement of the article in the direction in which said tampon end portion extends from the applicator tube, and means having a forming-receptacle for receiving and shaping said projecting tampon end portion as an incident to 10 said last mentioned endwise movement of the article.

10. In apparatus for conditioning an article embodying a tampon seated in an end portion of an applicator tube and projecting from an 15 end thereof, and an ejector tube telescoped into the other end portion of said applicator tube and projecting therefrom, said apparatus comprising means for propelling said article laterally, step by step, guide members spaced from each other to receive between them the transverse thickness of said articles, one of said guides being provided with a shoulder extending in the direction of travel of said articles and adapted to be engaged by the ejector receiving end of 20 said applicator tube for positioning said applicator tube, reciprocating means operative in one position of rest of the article to engage the outer end of the ejector tube to effect lengthwise movement of the article for positioning said applicator tube to permit engagement of said ejector receiving end of said applicator tube with 25 said positioning shoulder, means operative in another position of rest of said article to engage the projecting tampon end portion so as to press the tampon inwardly of the applicator tube and the applicator tube against said positioning shoulder, and means operable in another position of the applicator tube to engage the free end of said ejector tube to effect endwise 30 movement of the article in the direction in which said tampon end portion extends from the applicator tube, and means having a forming-receptacle for receiving and shaping said projecting tampon end portion as an incident to said 35 last mentioned endwise movement of the article, said receptacle means being provided with a shoulder adapted to be engaged by the adjacent end of said applicator tube to limit endwise movement whereby said forming chamber 40 is also operative to determine the extent to which said tampon projects from said applicator tube. 45

11. Apparatus for conditioning elongated article assemblies, each of which embodies an applicator tube, a tampon seated in one end portion of said applicator tube with an end portion of said tampon accessible adjacent one end of said applicator tube, and an ejector tube having a portion of its length telescoped into the other end portion of said applicator tube, said 50 apparatus comprising means for intermittently propelling said article assemblies transversely of their lengths, guides extending in the direction of travel of said articles for maintaining the same within a predetermined path of travel, 55 60 65

reciprocable plungers respectively disposed on opposite sides of said path of travel and adapted to act on the opposite ends of said articles, a rotating cam, and means operatively connecting said cam to said plungers for effecting simultaneous reciprocation of the latter in opposite directions, said plungers being respectively operative to adjust said tampon and said ejector tube inwardly of said applicator tube to predetermined positions therein, means disposed adjacent to one side of said path of travel in spaced relation to said plungers and adapted to act on the accessible end portions of said tampons to work and thereby soften said end portions, and means for actuating said working means, said plungers and said softening means being operative on said article assemblies while in said path of travel.

12. Apparatus for conditioning elongated article assemblies, each of which embodies an applicator tube, a tampon seated in one end portion of said applicator tube with an end portion of said tampon accessible adjacent one end of said applicator tube, and an ejector tube having a portion of its length telescoped into the other end portion of said applicator tube, said apparatus comprising means for intermittently propelling said article assemblies transversely of their lengths, guides extending in the direction 20 of travel of said articles for maintaining the same within a predetermined path of travel, a pair of reciprocable plungers disposed on opposite sides of said path of travel in alignment with each other and adapted to embrace one 25 of said articles, said plungers being rigidly inter-connected for unitary reciprocation, means for effecting such reciprocation of said plungers, and a tampon end shaping socket in alignment with said plungers for receiving and shaping said projecting end portion of a tampon when the tampon is moved endwise in one direction by one of said plungers, the other of said plungers being operative within the area of said socket to eject said tampon end portion from said socket. 30 35 40
